CHARLES SAMUEL FRANKLIN, OF BUCKHURST HILL, AND ERNEST GREEN, OF HENDON, LONDON, ENGLAND, ASSIGNORS TO RADIO CORPORATION OF AMERICA, A CORPORATION OF DELAWARE

CIRCUIT ARRANGEMENT

Application filed September 28, 1927, Serial No. 222,602, and in Great Britain October 2, 1926.

This invention relates to electrical energy transferring, transforming, coupling and the like devices, and more particularly to such devices for use in high frequency circuits, 5 such as radio circuits.

In many cases, for example, in feeders for supplying high frequency energy to the aerials of an aerial system, it is desirable that the coupling or the like device for transferring 10 energy from the feeders shall impose a certain specified effective load, generally that of a non-inductive resistance equivalent to the surge impedance of the feeder, upon the said feeder. It has been usual to employ air 15 core magnetic transformers, as such coupling devices, but such transformers are not well adapted for this purpose, since they require to be compensated for the effects of magnetic leakage and reactive loads.

According to this invention an energy transferring, transforming, coupling or the like device, for use in high frequency circuits, comprises a shunt and/or series reactance or reactances inserted between the feeder 20 and the actual load, whereby the effective load upon the said feeder may be given the required character.

The reactance or reactances may be formed of either "lumped" or distributed inductances 25 and capacities.

The invention is illustrated in the accompanying drawing in which:

Fig. 1 shows diagrammatically one form of the invention;

Fig. 2 shows diagrammatically a second form thereof, and

Fig. 3 shows diagrammatically the invention as arranged to feed current to a plurality of aerials.

Figure 4 shows diagrammatically another form of the invention.

Referring to Figure 1, a coupling or the like device comprises an inductance L in series with, and a capacity C in shunt to, the feeder. If it be desired to step-up the output resistance to a higher value, the feeder should be connected to the terminals X , Y , which therefore become the output of the line and the input or primary terminals of the transformation, while the terminals A , B , consti-

tute the output or secondary terminals of the transformation. Conversely, if it be desired to step down the output resistance, the feeder should be connected to the terminals A , B , which thus become the input or primary 55 terminals.

To take a numerical example, if the load on the secondary is a resistance R and a primary load of $2R$ is required, then the inductance L should have a reactance of R ohms, and the 60 capacity a reactance of $2R$ ohms at the frequency employed.

In the modification illustrated in Figure 2, the capacity C is connected in series with the feeder and the inductance L in shunt thereto. In such an arrangement, for the same 65 conditions of load and desired load as in the previous numerical example, the reactance of the capacity should be R ohms and that of the inductance $2R$ ohms. 70

Where the secondary load is reactive as well as resistive, the value of the inductance and/or capacity may be adjusted to compensate for this.

A particular example of the use of such a coupling device arises in a system of high frequency power distribution, for example, for feeding a plurality of aerials in an aerial system. Such a system may comprise a main section of feeder leading from a source of 75 high frequency energy to a coupling device whose secondary feeds two further sections of feeder in parallel. Each further section of feeder may similarly supply through a coupling device two more sections of feeder, 80 each of which supplies, through a yet further coupling device, an aerial. In order that stationary waves and consequent excessive losses and voltage stresses may be prevented, it is necessary to make the effective terminal 85 load on any section of feeder equal to the surge impedance of that section which is practically a pure resistance. The coupling devices hereinbefore described provide a convenient means of effecting this. For example, if the feeder has a surge impedance of R_s throughout and the output loads are correct, the coupling device at each junction point 90 will be required to step-up the load from $\frac{1}{2}R_s$ to R_s .

95

100

Figure 3 illustrates an embodiment in which a coupling device according to the present invention is provided in such a system of high frequency power distribution for feeding a plurality of aerials. Referring to the figure, the main section of feeder M leading from a source of high frequency energy is connected at the primary side A, B, of the coupling device, the two further sections S1 and S2 of feeder being connected in parallel at the secondary side X, Y, of the said coupling device.

The arrangement illustrated in Figure 3 is clearly reversible and may thus be employed for collecting energy from a plurality of receiving aerials.

If desired the coupling device may comprise a substantially uniform length of feeder, an appreciable fraction of a wave length long inserted in series between a feeder and its load, and so adjusted as to give an effective load of the required character upon the said feeder. If the surge impedance of a length of feeder is not equal to the load at the output end thereof, stationary waves of voltage and current occur in the said length, so that the equivalent impedance of the said length with its load varies at different points along the said length, and this phenomenon is utilized in the present construction by making the inserted length of feeder of such characteristics that the required load transformation is effected. For example if R_o is the surge impedance of the length of feeder and $2R_o$ the terminal load, the equivalent impedance of the load and feeder at a distance of one quarter wave length from the load is a non-inductive resistance of $\frac{1}{2}R_o$; that is to say, a load of $2R_o$ is effectively transformed into one of $\frac{1}{2}R_o$. In general, if R_1 is the load resistance and R_2 the required effective resistance, a quarter wave length of feeder of surge impedance

$$45 \quad \sqrt{R_1 R_2}$$

is inserted as a coupling device.

It will be apparent that any type of load may be thus transformed into any other type.

If desired, the inserted length of cable may be replaced by an artificial line.

Constructions in which the coupling device comprises an inserted cable or artificial line may be employed conveniently in aerial feeder systems such as that already described herein. For example, in the said described system in which each coupling device is required to step-up a load from $\frac{1}{2}R_o$ to R_o , the said coupling device may comprise a length of cable or artificial line, one quarter of a wave length long and of surge impedance

$$60 \quad \sqrt{\frac{1}{2}R_o R_o} = \frac{R_o}{\sqrt{2}}$$

Having now particularly described and ascertained the nature of our said invention

and in what manner the same is to be performed, we declare that what we claim is:

1. An arrangement for matching the impedance of branched high frequency transmission lines comprising a first transmission line, other transmission lines connected in parallel, and means for coupling the first transmission line to the parallel connected transmission lines comprising a reactance of one sign connected in series with the first line, and a reactance of opposite sign connected in shunt across the first line. 70

2. An arrangement for matching the impedance of branched high frequency transmission lines comprising a first transmission line, other parallel connected transmission lines, and means coupling the first transmission line to the parallel connected transmission lines comprising a reactance of one sign connected in series with the first transmission line, and a reactance of opposite sign connected across the first transmission line between said transmission line and the aforesaid series reactance. 80

3. An arrangement for matching the impedance of branched high frequency transmission lines comprising a first transmission line, other parallel connected transmission lines, and means coupling the first transmission line to the parallel connected transmission lines comprising a reactance of one sign connected in series with the first transmission line, and a reactance of opposite sign connected across the first transmission line between said transmission line and the aforesaid series reactance, the magnitude of the latter reactance being equal to the surge impedance of the first transmission line, and the reactance of the series combination of both the aforesaid reactances being equal to the surge impedance of the other transmission lines connected in parallel. 90
